(57) **CLAIM**

The ornamental design for a calendar sheet, as shown and described.

DESCRIPTION

FIG. 1 is a plan view of the calendar sheet showing my new design;

FIG. 2 is an enlarged fashion view of the top left quadrant of the calendar sheet of FIG. 1;

FIG. 3 is an enlarged fragmentary view of the top right quadrant of the calendar sheet of FIG. 1;

FIG. 4 is an enlarged fragmentary view of the bottom left quadrant of the calendar sheet of FIG. 1; and,

FIG. 5 is an enlarged fragmentary view of the bottom right quadrant of the calendar sheet of FIG. 1.

The rear of the calendar sheet is flat and plain and the sheet is of conventional thickness.

The stippled shading in the drawing indicates color contrasts.

The broken line showing of the text in FIGS. 1 through 5 is for illustrative purposes only and forms no part of the claimed design.
